UNITED STATES PATENT OFFICE.

GEORGE E. DALE, OF TRENTON, NEW JERSEY, AND MICHAEL J. O'MEARA, OF PHILADELPHIA, PENNSYLVANIA; SAID O'MEARA ASSIGNOR TO SAID DALE.

HOLLOW-TILE FLOOR CONSTRUCTION.

Application filed October 29, 1921. Serial No. 511,333.

To all whom it may concern:

Be it known that we, GEORGE E. DALE and MICHAEL J. O'MEARA, citizens of the United States, residing, respectively, in Trenton, New Jersey, and Philadelphia, Pennsylvania, have invented certain Improvements in Hollow-Tile Floor Construction, of which the following is a specification.

Our invention relates to certain improvements in what is known as a "two-way floor construction", in which tiles are set in concrete, which is reinforced by transverse and longitudinal bars.

The object of our invention is to make a tile so that two tile sections, similar in construction, can be assembled to form a tile unit closed at top and bottom and on all four sides. When several of these units are located in a floor and surrounded on the sides with concrete, the top and bottom of said tile units act as compression members.

In the accompanying drawings:

Fig. 1 is a plan view of a floor illustrating our invention;

Fig. 2 is a sectional view on the line 2—2, Fig. 1;

Fig. 3 is a sectional view on the line 3—3, Fig. 1;

Fig. 4 is a perspective view showing two tile sections assembled to form tile units.

Fig. 5 is a view of a tile block as it comes from the mold after being burned;

Fig. 6 is a view showing the tile block illustrated in Fig. 5, cut and parts of the center webs removed;

Fig. 7 is a view showing two sections turned at right angles to each other so that they can be assembled to form the tile unit illustrated in Fig. 4;

Fig. 8 is a perspective view illustrating a modification of the invention;

Fig. 9 is a sectional view of the tile sections, shown in Fig. 8 assembled; and

Fig. 10 is a view illustrating another form of tile.

Referring to the drawings, 1 is the floor. 2 are posts spaced a given distance apart. 3 and 4 are concrete beams which extend from one post to the other. In the space between these beams is a series of tile units 5 spaced apart, as shown in Figs. 1, 2 and 3. In the spaces between the tile units are longitudinal bars 6 and transverse bars 7. The

space between the tile units is filled with 55 concrete. This construction forms what is known as a "two-way floor construction".

Each tile unit consists of two tile sections 8 and 9. These tile sections are made, in the present instance, from a tile block 10, 60 as illustrated in Fig. 5. This tile block has a continuous top member 11 and a continuous bottom member 12 connected by sides 13 and intermediate webs 14. This tile block can be made in an ordinary tile machine. 65

The block is cut, as shown in Fig. 6, into two sections 8 and 9. The webs 14 are reduced in length by removing the portions 70 15. One section is turned at right angles 75 in respect to the other so that the two sections can be assembled, as shown in Fig. 4, the openings in the ends of one tile section being closed by the ends of the other tile section so that the tile unit has a continuous upper surface, as well as a continuous lower surface and all four sides are closed. The division is in a plane, or planes, parallel to the general plane of the floor. 75

In Fig. 8, a modification of the invention is illustrated, in which the two tile sections 8^a and 9^a are identical in form, each having a section which extends over the full width of the tile, as in Fig. 9, and having vertical webs 16, which cross each other, as shown. 80 Projections 17 on one section are adapted to recesses 18 in the other section so that when the two tile sections are assembled, as in Fig. 9, the upper surface of one section and the lower surface of the other section form 85 continuous members, and the parting is on planes parallel to the plane of the floor. 90

In Fig. 10 we have illustrated another modified form of a tile section having a flat unbroken surface 11^a connected by webs 95 19 with an inner web 20 and having hollow flanges 13^a. This particular construction forms the subject of a separate application for patent.

In assembling the tile units in a floor, 100 they are spaced apart, as shown in Figs. 1, 2 and 3. The metallic rods are placed in position, after which the concrete is poured in the spaces between the tile units to the same depth as the tile units, as shown in Fig. 2, so that the lower portion of each lower tile can act as a lower compression member, as the concrete is in direct contact 105

with the tile. The upper portion of the upper tile can act as an upper compression member, as the concrete is in direct contact therewith.

5 While the term "hollow tile units" is used in the claims, it will be understood that the units may be made of baked clay, concrete, with or without reinforcements, or any other material that will sustain a load under compression.

10 We claim:

15 1. A hollow tile unit formed of two similar tile sections, each of said sections having end flanges adapted to cooperate with and overlap the sides of the opposing section to form a tile unit closed on all four sides, the end edges of said flanges forming oppositely presented external shoulders, and means for maintaining the said end-edges 20 of the flanges between the top and bottom planes of the assembled unit.

25 2. A hollow tile unit formed of two similar tile sections, each having parallel end flanges and parallel webs intermediate, and of less length than, the end flanges, the tile sections in the unit having their flanges at right angles, with the end flanges of each section closing the sides of the other section and offset outwardly beyond said sides to 30 form external shoulders, and the intermediate webs engaging one another and serving to hold the ends of the said shoulder-forming flanges between the top and bottom surfaces of the unit.

35 3. A hollow tile unit comprising two similar tile sections each having a top member and two oppositely arranged end flanges, the distance between the inner surfaces of said end flanges being equal to the width of 40 the top members so that when one section is inverted, turned at right angles and assembled within the other, the two sections form

a tile unit closed on all four sides and having oppositely presented external shoulders, and means for maintaining the shoulder-forming end edges of the said end flanges between the top and bottom planes of the assembled unit.

4. A hollow tile unit comprising two similar tile sections, each having a top member and two oppositely arranged end flanges, the distance between the inner surfaces of said end flanges being equal to the width of the top members so that when one section is inverted, turned at right angles and assembled within the other, the two sections form a tile unit closed on all four sides and having oppositely presented external shoulders, and webs carried by each top member between said flanges adapted to support the sections to maintain the upper and lower edges of the said end flanges between the top and bottom planes of the assembled unit.

5. A hollow tile unit comprising two similar tile sections, each having a top member and two oppositely arranged end flanges, the distance between the inner surfaces of said end flanges being equal to the width of the top members so that when one section is inverted, turned at right angles and assembled within the other, the two sections form a tile unit closed on all four sides and having oppositely presented external shoulders, and a series of inwardly projecting webs carried by each top member between said flanges, said webs being less in height than the end flanges and when engaged, supporting the sections to maintain the upper and lower edges of the said end flanges between the top and bottom planes of the assembled unit.

GEORGE E. DALE.
MICHAEL J. O'MEARA.
